UNITED STATES PATENT OFFICE.

GEORGE MAY, OF SAN FRANCISCO, CALIFORNIA, ASSIGNOR OF ONE-HALF TO EMILY SCHMIDT, OF SAN FRANCISCO, CALIFORNIA.

METHOD OF MAKING BOILER TUBING.

Application filed February 12, 1924. Serial No. 632,390.

To all whom it may concern:

Be it known that I, GEORGE MAY, a citizen of the United States, residing at San Francisco, in the county of San Francisco and State of California, have invented new and useful Improvements in Methods of Making Boiler Tubing, of which the following is a specification.

The present invention resides in the provision of an improved tubing and method of making the same, which tubing is particularly adapted for use in boilers, steam generators, water heaters and the like, and for all purposes wherein fluids are heated in tubing.

The primary object of the invention is to provide a simply constructed and comparatively inexpensive tube construction which is of substantially oval form in cross section and provides a greater heating surface in proportion to its sectional area than is provided with the usual round or circular tubing, the method by which the tubing is made being more simple and less expensive to carry out as compared to methods employed in making round tubing.

A further object of the invention is to provide a tubing construction of the character described which may be quickly and easily formed from elongated strips of sheet, strap or like metal and which, due to the cross sectional shape of the tubing, will provide for a quicker heating of water or quicker generation of steam, depending on the use of the tubing, than is possible with the ordinary round or circular tubing.

A further object is to provide an improved tubing construction and method of making the same which makes possible the use of a cheaper grade of metal than is employed for the usual form of round or circular tubing, without sacrificing any of the advantages of such round or circular tubing, and with the added advantages of cheapness of construction, greater heating area, and quicker heating of the water.

With the above mentioned and other objects in view, the invention consists in the novel construction and combination of parts hereinafter described, illustrated in the accompanying drawings, and set forth in the claims hereto appended, it being understood that various changes in the form, proportion, size and minor details of con-

struction within the scope of the claims may be resorted to without departing from the spirit or sacrificing any of the advantages of the invention.

Referring to the drawing:

Fig. 1 represents a cross sectional view of the initial form into which the strip of metal is bent in the method of forming the tubing, the strip being shown, as before being bent, in dotted lines.

Fig. 2 represents a sectional view of the tubing in its next form.

Fig. 3 represents a cross sectional view of the finished tubing.

Fig. 4 represents a perspective view shown partly in cross section, of the means employed for bending the tubing into coils.

Fig. 5 represents a top plan view of a finished coil of tubing constructed in accordance with the invention.

In the present embodiment of the invention, the tubing is constructed from an elongated strip 1 of thin sheet or strap metal, of any suitable character, which strip is shown in dotted lines as before being initially treated in the carrying out of my invention. As shown in Fig. 1, the first step in the forming of the tubing of my invention requires the bending of the strip into channel or U-form shown at A. This may be carried out in any suitable manner providing for a quick and inexpensive bending of the strip into such form. After the strip is bent into channel or U-form, a length or strip of wire or other substance 2, which will serve as a closure, is mounted in and closes the open side of the U-shaped tube. This length or strip of wire or other material is such that it will fit snugly in the open side of the tubing. After placing the strip as shown, said strip is welded, as shown at 3, in Fig. 3, to the sides of the tubing, preferably being done by an electric welding. By welding the closure strip 2, the open side of the tubing is sealed and the finished tubing is of substantially oval shape in cross section. It will thus be seen that the formation of tubing in accordance with the invention takes into consideration but three steps, namely, the bending of the strip into U or channel form, the placing of the closure wire or strip, and the welding of this closure member in place.

If the tubing of the invention is to be coiled, and this is usually the form in which

the tubing is made, before the second and third steps are carried out, that is the placing of the closure strip and the welding thereof in place, a bendable metal form retaining strip 4 is placed in the U-shaped form of the tubing as shown in Fig. 4, and preferably so that it extends beyond the edges of the open side of the tubing. This strip 4 is of the proper diameter to maintain the sides of the tubing in parallelism and to maintain the U-shaped form throughout the bending operation. The next step is to place on one side of the tubing a bendable metal spacing strip 5 corresponding in shape and form to the strip 4, and the tubing is then bent in a suitable bending machine, not shown, around the strip 5 which acts as a spacing member to provide an equal spacing of the coils formed in the bending operation. The strip 5 may be of different thicknesses, as desired, depending on the spacing of the coils desired. With the parts assembled as shown in Fig. 4, the assembly is suitably fed into a bending machine which may be operated to form the coil, for example, the coil B, in Fig. 5. After the coil is formed, the second and third operations, in forming the tubing are carried out, the strip or other material 2 being placed in the open side of the coil and then welded as shown in Fig. 3, thus completing the formation of a coil of tubing of the special construction of this invention.

In Fig. 5, there is shown a flat coil but I do not limit myself to the shape shown as it is obvious that the tubing may be formed into coils of various sizes and shapes. Suitable couplings or joint members, not shown, may be provided for connecting water feed and return pipes, not shown, to the terminals of the coils, shown in Fig. 5, which coupling members may be welded thereto or otherwise attached as desired, to said terminals.

In carrying out the method and construction of this invention, it is seen that I may use any suitable kind of sheet or strap metal in strips, depending upon the grade or character of the tubing desired, to quickly and easily form the strip into a substantially oval tube, which tube has a greater heating surface in proportion to the cross sectional area or water capacity than is provided in the ordinary round or cylindrical tubing, with a result that when such tubing is used for

boilers, water heaters or the like, the water will be heated or the steam generated more rapidly than is possible with the conventional form of round tubing. The construction provided by the invention will tend towards greater durability, strength and length of life in boiler and water heater tubing than is possible with the conventional round type of tubing and due to the simplicity of the method followed in making the tubing, a great saving in time and expense in the manufacture of the tubing may be effected. In forming the coils with the use of the strips 4 and 5 after the tubing is bent into the desired coil form, the strips may be readily removed by being knocked out with a suitable tool or instrument, not shown, and in some instances, can be lifted out of place.

If desired, the first operation of bending of the strip of metal into U or channel form, may be carried out by making such bend around the strip 4 and the coiling operation may be carried out by then placing the bendable strip 5 on one side of the U-form and then carrying out the coil forming operation as described.

I claim:

1. The method of constructing tubing in coil form which consists in first bending a strip of metal into channel form, placing a form retaining bendable strip in the channel of the form, placing a bendable strip on one side of said form then bending the form and strips to form a coil or series of coils, then removing said bendable strips, then sealing the open side of the channel.

2. The method of constructing tubing in coil form which consists in first bending a strip of metal into channel form, placing a form retaining bendable strip in the channel of the form, placing a bendable strip on one side of said form then bending the form and strips to form a coil or series of coils, then removing said bendable strips, then placing a sealing strip into the open side of said channel, then welding said strip to said form.

3. A coil of substantially flat tubing having a substantially ovoidal form in cross section, which tubing is made up of a sheet of metal bent into channel form and a closing strip welded in the open side of the channel of said form.

GEORGE MAY.
